CLAIM

I claim the ornamental design for a floor fixer, as shown and described.

DESCRIPTION

FIG. 1 shows a front view of the floor fixer;

FIG. 2 shows a perspective front view thereof;

FIG. 3 shows a top perspective view thereof;

FIG. 4 shows the side perspective view thereof; and,

FIG. 5 shows a bottom perspective view thereof.

The dash-dash broken lines depict portions of the invention that form no part of the claimed design.
